UNITED STATES PATENT OFFICE

2,388,832

CONTROL MECHANISM

William W. Criley, Shaker Heights, Ohio, assignor
to The Ajax Manufacturing Company, Cleve-
land, Ohio, a corporation of Ohio

Application March 24, 1942, Serial No. 435,981

7 Claims. (Cl. 192—139)

The present invention relates to an improved mechanism for effecting the "non-repeat" operating control of a metal working machine such as a forging machine, forging press and the like. A manual control device such as a foot treadle or hand lever is customarily provided for initiating the working stroke or operating cycle of such a metal working machine, involving the engagement of the clutch and the release of the brake in the machine driving train. Automatic, machine actuated means are likewise provided on such machines for subsequently controlling the clutch and brake operation to the end of a single working cycle. It is highly desirable, not only for the purposes of human safety, but also for the proper operation of the metal working machine at the production rate for which it has been designed, to provide automatic means for preventing the machine from repeating one operating cycle after the other without an intervening manipulation of the manual control by the operator. Such a latter automatic control device has been conveniently termed a "non-repeat control."

In my co-pending application Serial No. 331,117, filed April 23, 1940, I have disclosed a structure for accomplishing the same, above outlined general objective. The present invention, however, constitutes an improvement over such structure of my aforesaid co-pending application in that it embodies a greatly simplified construction, involving the elimination of extra valves, pressure lines and mechanical parts, while retaining the achievement of the same ultimate function.

It is one of the objects and advantages of the present invention to incorporate the control valve, which operates to secure the non-repeat operation of the machine, directly into the manual control valve structure, whereby the non-repeat control may be applied to the metal working machine in a convenient and simplified manner.

Briefly outlined, the improved structure embodying the principle of my invention consists of the incorporation of a valve means connected in series with the manually operated control valve and operated by pressure from the clutch pressure actuating line for shutting off and rendering inoperative the manual control valve during each operating cycle, thus requiring an intervening resetting movement of the manual control valve before another working cycle of the machine may be instituted.

To the accomplishment of the foregoing and

related ends, said invention then comprises the features hereinafter fully described and particularly pointed out in the claims, the following description and the annexed drawing setting forth in detail certain illustrative embodiments of the invention, these being indicative, however, of but a few of the various ways in which the principle of the invention may be employed.

In said annexed drawing—

10 Fig. 1 is an elevational view illustrating the control mechanism embodying the principle of my invention as applied to a metal working machine such as a forging press;

15 Fig. 2 is a sectional view taken through the manual control valve or foot treadle, showing the auxiliary non-repeat valve incorporated therein; and

20 Fig. 3 is a view similar to Fig. 2 but showing an alternative form of construction for the auxiliary valve proper.

Now referring more particularly to the drawing, Fig. 1 shows the frame of a forging press as indicated at 1 upon which the electric drive motor 2 is mounted and connected by means of a drive belt to the fly wheel of the pressure actuated clutch 3 mounted either upon the high speed shaft (as shown in the drawing) or on the main shaft. A pressure actuated control valve 4 (alternatively called a timer valve) is adapted to receive pressure from the main supply line 5 and through the accumulator tank 6 to control and distribute actuating pressure through the clutch control line 7 and the brake control line 8.

35 A cam 9, mounted upon the main shaft 10, contacts with the follower 11, and the motion of the latter is transmitted through the push rod 12 to the control valve 4. These elements constitute the machine actuated mechanism for controlling the operation of the clutch and brake after the operating cycle of the machine has been once instituted.

40 The above described elements of the mechanism are illustrated and described in detail in my co-pending application Serial No. 390,092, filed October 24, 1941, and hence need not be here further described or set forth.

45 A manual control valve, such as the foot lever indicated generally at 13, is also connected to the main supply line 5 and to the pressure actuated control valve 4 through the line 14. A line 15 leads from the clutch pressure control line 7 to the foot treadle 13.

50 The operating parts of the foot treadle valve or manual control valve are shown in Fig. 2. 55 The main pressure supply line 5 (which may be

from the shop air pressure line) enters the intake chamber 20. The outlet port 21 leads from the chamber 20 to the passage 23 and is adapted to be opened and closed by the spring loaded poppet valve 22. The passage 23 leads to the second valve chamber 24 having an exhaust outlet therein which is opened and closed by the spring loaded poppet valve 26. The passage 27 places the exhaust outlet 25 in communication with the atmosphere.

The valve chamber 24 is in communication with the inlet passage 28 leading to the cylindrical bore 29 in which the sliding piston, or "dumb-bell" type valve 30 is reciprocably mounted.

The bore 29 is located in the block or casting 31 attached to the base plate 13 of the foot treadle structure. The casting or housing 32, containing the poppet valves 22 and 26 and their pertinent parts, is fitted upon and attached to the casting 31 by means of the studs as indicated at 33 and the gasket 34.

An outlet port 35, in registry with the inlet 28, leads to the conduit or line 14 going to the pressure actuated control valve or timer 4. A branch passage 36 leads from the port 35 to the second port 37 in registry with the exhaust port 38 which communicates with the exhaust outlet 39 leading to the atmosphere. A reduced diameter portion 40 on the valve 30 is adapted to place the ports 28 and 35 in registry when the piston valve 30 is in its lowermost position as indicated by the dotted lines in Fig. 2. Another reduced diameter portion 41 places the ports 37 and 38 in communication when the piston valve 30 is in its uppermost position as shown by the full lines in Fig. 2. A passage 42 leads from the clutch pressure control line 15 to the bottom, closed end of the bore 29.

The upper end of the piston valve 30 has a shoulder 43 which is adapted to contact with a stop plate 44, thus limiting upward movement of the valve 30.

A manipulating lever in the form of the foot treadle 45 is oscillatably mounted upon the fulcrum pin 46. The lower or right-hand end 47 of the foot treadle 45 consists of a foot plate adapted to be stepped upon and depressed by the operator's foot, into the position as shown in Fig. 2.

The upper or left-hand end 48 of the foot treadle 45 is in the form of a rocker arm adapted to contact with the upper end of the piston valve 30.

The foot treadle 45 also has a projecting lug 49 adapted to contact with the valve trip bar 50 which is pivoted on the pin 51, and in its alternative positions of movement, adapted to trip or open the poppet valves 22 and 26, respectively.

A coil compression spring 52 bearing against the lower end of the trip bar 50, and held in place by the guide stud 53, urges the trip bar in a counter-clockwise direction and with sufficient force to open the poppet valve 26. A return spring (not shown) is provided for urging the foot treadle in a counter-clockwise direction and into such position corresponding to a release of foot pressure upon the foot plate 47.

The operation of the above described mechanism is as follows:

In order to start the machine upon its working cycle, the operator depresses the foot plate 47 to the position as shown in Fig. 2. This opens the valve 22 permitting pressure from the line 5 to be transmitted to the inlet 28 of the valve 30 which is in the position as shown by the dotted

lines. Such pressure is then communicated through the outlet port 35 to the line 14 to actuate the timer valve 4 which in turn admits pressure from the accumulator tank 6 to the clutch and brake lines 7 and 8; whereupon the brake is released and the clutch 3 engaged causing the machine to start upon its working stroke. The cam 9, by cooperation with the follower 11 and push rod 12, then controls the operation of the timer valve 4 and the admission of pressure to the clutch and brake lines 7 and 8, respectively, during the remainder of the working cycle of the machine.

When pressure is admitted to the clutch pressure line 7, it is also transmitted through the line 15 to the passage 42 to the bottom end of the piston valve 30, forcing the latter to its upper position in the bore 29, as shown by the full lines in Fig. 2. When the valve 30 is in this latter position, the inlet port 28 is closed and the port 37 is opened to the exhaust port 39, thus exhausting any pressure in the line 14 leading to the timer valve 4 and preventing pressure actuation of the latter. Accordingly, in order for the operator to again start the machine on a working cycle, it is necessary to release foot pressure upon the foot treadle 45 and permit the latter to rotate in a counter-clockwise direction, whereupon the rocker arm 48 moves down against the upper end of the valve 30, resetting the latter to its original starting position as shown by the dotted lines.

It will thus be seen that the above described mechanism and its mode of operation requires the operator to manipulate or release his foot pressure upon the foot treadle valve lever 45 at the end of each working cycle of the machine before it can be started on another one.

In the form of construction shown in Fig. 3, a hollow, ported-wall, piston valve is used in place of the previously described solid or dumb-bell form of piston valve. Thus, in Fig. 3 the main pressure supply line 5, just as in the form of Fig. 2, is similarly connected to the intake chamber 20 in which the valve 22 is mounted. The hollow, sliding piston valve 61 has an enlarged head or piston 62 on its lower end, and the passage 63 leads from the clutch control pressure line 15 to the head end of the cylinder in which such piston 62 is fitted. The hollow piston valve 61 has the spaced wall ports 64 and 65, which, when the valve 61 is in lowermost position, are adapted to place the intake port 28 and the outlet port 69 in communication with the line 14 leading to the timer valve 4. In the lower portion of the valve 61 are located the spaced wall ports 67 and 68, which, when the valve 61 is in the position as shown in Fig. 3, are adapted to place the port 69 in communication with the exhaust port 60 leading to the atmosphere.

Leather or fiber washers 70 and 71, compressibly held in place by the compression spring 72, are mounted between the outer wall of the valve 61 and inner wall of the housing 31 for slidably sealing the valve 61 and the ports 64 and 65 in their alternative operating positions. A similar washer is provided, as indicated at 72, for the ports 67 and 68.

The operation of the last described alternative structure of Fig. 3 is the same as that previously recited in connection with Fig. 2; pressure from the line 15 causing the valve 61 to be moved into an upward position and requiring a release or resetting movement of the foot treadle 45 to move

the valve 61 into downward position before the machine can again be started.

Other modes of applying the principle of the invention may be employed, change being made as regards the details described, provided the features stated in any of the following claims or the equivalent of such be employed.

I therefore particularly point out and distinctly claim as my invention:

1. A control mechanism for a metal working machine in which machine there are present a pressure actuated clutch for engaging the driving train of said machine, a pressure actuated valve for introducing pressure to said clutch, and machine actuated mechanism for closing said pressure actuated valve after one cycle of operation of said machine, the improvement comprising a unitary, combined manually actuated and pressure actuated control valve for controlling the introduction of pressure to said pressure actuated valve, said control valve being manually operable to introduce pressure to said pressure actuated valve, and pressure actuated to shut off pressure to said pressure actuated valve, and means connecting pressure introduced to said clutch to said control valve.

2. In a control mechanism for a metal working machine in which machine there are present a pressure actuated clutch for engaging the drive mechanism of said machine, a pressure supply source, a manual valve connected to said supply source for controlling the introduction of pressure to said clutch, machine actuated mechanism for disconnecting the introduction of pressure to said clutch, the improvement comprising a pressure actuated valve operable to shut off pressure from said manual valve to said clutch, and a conduit communicating the pressure introduced to said clutch to said pressure actuated valve.

3. A control mechanism for a fluid operated device comprising a manually actuated first valve means for controlling the introduction of pressure alternately to an outlet and to an exhaust and a pressure piston actuated valve connected in series with said first valve means, means for introducing pressure from the fluid operated device against the piston of said piston actuated valve to move it to closed position, and means connecting the other end of said piston actuated valve to the manipulating movement of said first valve means to move said piston valve to open position.

4. In a control mechanism for a fluid operated device comprising a manual valve, a pressure piston actuated valve connected in series with said manual valve, a conduit connecting pressure from the fluid operated device against the piston of said piston actuated valve to move the latter to closed position, and means connecting the other end of said piston actuated valve to the

manipulating movement of said manual valve to move said piston actuated valve to open position.

5. A control mechanism for a fluid operated device comprising a manually operated valve body having a dual set of valves mounted therein, each of said valves having an inlet, an outlet and an exhaust, the inlet of one of said valves being connected to a supply source, the inlet of the other of said valves being connected to the outlet of said one of said valves, the outlet of said other of said valves being connected to the fluid operated device, an oscillatable lever movable in one direction to open said first inlet and movable in the opposite direction to open said second outlet and simultaneously to open the exhaust on said one of said valves, and pressure actuated means connected to the fluid operated device for moving said other of said valves to a position closing its inlet and opening its exhaust.

6. A control mechanism for a fluid operated device comprising a manually actuated first valve means for controlling the introduction of pressure from a supply source alternately to an outlet and to an exhaust, and a pressure actuated second valve means alternately connecting and disconnecting the outlet of said first valve means with the fluid operated device, said second valve means being movable in one direction solely by pressure induced from the fluid operated device to so disconnect the outlet of said first valve means, and mechanical connecting means between said first valve means and said second valve means for moving the latter to so connect the outlet of said first valve means.

7. A control mechanism for a fluid operated device comprising a first valve means having a supply port, an outlet port, and an exhaust port and being operable between a first position connecting said outlet and said exhaust ports and a second position connecting said outlet and said supply ports, a second valve means having an inlet port, a service port, and a vent port and movable between a first position connecting said service and said inlet ports and a second position connecting said service and said vent ports, the outlet port of said first valve means being connected to the inlet port of said second valve means, and the service port of said second valve means being adapted to be connected to the fluid operated device, manually actuated means for operating said first valve means, fluid actuated means for moving said second valve means to its said second position, and means connected to said manually actuated means for moving said second valve means to its said first position when said first valve means is operated to its said first position.

WILLIAM W. CRILEY.
